UNITED STATES PATENT OFFICE.

OTTO J. DOERRE, OF CHICAGO, ILLINOIS.

GAME.

Application filed August 24, 1925. Serial No. 52,240.

My invention relates to games and particularly to games involving skill.

The object of the invention is broadly to provide an improved amusement device 5 which is relatively simple in construction.

In one embodiment of the invention, manually operable means is provided for propelling a ball through an arcuate path which is disposed in a vertical plane in such manner 10 that the balls may drop into pockets to which values have been assigned.

Many other objects and advantages of the construction herein shown and described will be obvious in those skilled in the art 15 from the disclosure herein given.

To this end my invention consists in the novel construction, arrangement and combination of parts herein shown and described, and more particularly pointed out 20 in the claims.

In the drawings, wherein like reference characters indicate like or corresponding parts:

Fig. 1 is a front elevation of apparatus 25 embodying the invention;

Fig. 2 is a vertical section looking from the rear of the improved apparatus;

Fig. 3 is a section taken on line 3—3 of Fig. 2;

Fig. 4 is a section taken on line 4—4 of Fig. 2;

Fig. 5 is a section taken on line 5—5 of Fig. 2;

Fig. 6 is a section taken on line 6—6 of Fig. 2;

Fig. 7 is a section taken on line 7—7 of Fig. 6; and

Fig. 8 is a section taken on line 8—8 of Fig. 2, a slide forming part of the apparatus 40 being shown in a changed position.

In the drawings I have shown a preferred embodiment of the invention as it is employed in connection with dispensing apparatus, but my invention is limited to this use 45 only to the extent defined in the appended claims.

Referring to the drawings, 10 is a cabinet comprising a bottom wall 11, side walls 12 and 13, a top wall 14 and a removable rear panel 15. The front of the cabinet 10 is preferably closed by a glass panel 17 and by a corner plate 18. Disposed intermediate the glass panel 17 and the rear panel 15 is a plate 20, which preferably extends from the bottom wall 11 to the top wall 14 and from the side wall 12 to the side wall 13,

the plate 20 being secured to these walls in any suitable manner. The space within the cabinet 10 to the rear of the plate 20 is divided into two chambers 21 and 22 by a 60 shelf 23. Secured to the outer edge of the shelf 23 is a vertically disposed board 24, which, together with the shelf 23 and the plate 20, forms a pocket 25 adapted to hold a supply of articles 26 which are to be vend- 65 ed. Disposed in an opening 27 provided in the shelf 23 is a U-shaped member 28 carried at the upper end of a lever 29 which is pivotally secured by a screw 30 to a slide 31, the slide 31 being mounted upon the 70 rear surface of the plate 20. The U-shaped member 28 is of sufficient size to permit one of the articles 26 to pass therethrough, but is not large enough to permit two or more of the articles 26 to pass therethrough 75 simultaneously. The construction is such that when the slide 31 is reciprocated in a manner hereafter described, the U-shaped member 28 agitates the articles 26 and permits one of the articles to pass through it 80 into a pocket 33 formed in the slide, a guide 34 being interposed between the U-shaped member 28 and the slide.

The top wall 14 is provided with a slot 36 through which a coin or token may be 85 inserted in the cabinet 10. Secured to the rear surface of the plate 20 and aligned with the slot 36 is a chute 37 which has its lower end aligned with a shallow groove 38 formed upon the inner surface of the slide 31. 90 Formed in the upper surface of the slide 31 is a notch 39 providing a shoulder 40 engageable by a dog 41, the dog 41 being pivotally secured by a screw 42 to the rear surface of the plate 20. A tension spring 41^a yieldingly urges the free end of the dog 41 against the slide 31. The groove 38 and the dog 41 are so proportioned that if a coin or token of a predetermined size is dropped through the chute 37 it will come to rest in the groove 95 38 and will be prevented from passing therethrough by the dog. If the slide 31 is moved to the right (Fig. 2), the coin or token will serve as a cam and raise the dog 41 out of the path of the shoulder 40 so that 100 the pocket 33 may be brought into alignment with an aperture 42^b formed in the plate 20. This movement of the slide 31 and the resulting movement of the dog 41 permits the coin or token to drop through the 105 groove 38. The aperture 42^b is aligned with a discharge aperture 43 formed in the corner 110

plate 18, a pocket 44 being formed on the outer side of the corner plate 18 into which the articles 26 may fall when they pass through the discharge aperture 43. Obviously, the purchaser may remove the vended articles from the pocket 44.

The means for moving the slide 31 to the right (Fig. 2) comprises a lever 45 pivotally secured by a screw 46 to the rear surface of the plate 20. One end of the lever 45 projects through the wall 12, as indicated at 47, and the other end thereof is provided with a cam track 48 engageable with a slot 49 formed in the slide. The cam track 48 is so designed that when the outer end 47 of the lever 45 is depressed into the position wherein it is shown in dotted lines in Fig. 2, the slide will be moved to the position wherein it is shown in dotted lines in the same figure. This dotted line position of the slide 31 is the position wherein its pocket 33 registers with the aperture 42 formed in the plate 20. The outer end 47 of the lever 45 cannot be moved into the position wherein it is shown in dotted lines in Fig. 2 unless a coin or token is properly disposed in the groove 38, as the shoulder 40 will then engage the dog 41 and prevent displacement of the slide. Means for retracting the slide 31 and the lever 45 comprises a plurality of tension springs 31^a, one end of each spring 31^a being secured to the spring 31 and the other end thereof being secured to a screw 31^b projecting from the rear surface of the plate 20.

Formed on the front surface of the plate 20 is a substantially arcuate track 51, one end of which terminates in a substantially straight track 52 and the other end of which terminates in a pocket 53 formed upon the front surface of the plate 20 (Fig. 7). Formed in the plate and registering with the lower end of the pocket 53 is an aperture 55 with which a pocket 57 formed in the slide 31 registers when the slide is in the position wherein it is shown in full lines in Figs. 2 and 4. When the slide 31 is brought into the position wherein it is shown in dotted lines in Fig. 2, the pocket 57 registers with an aperture 58 formed in the plate 20. The arrangement is such that balls 60 of wood or any other suitable material may be fed from the pocket 53 to the substantially straight track 52. Thus, when the slide 31 is in the position wherein it is shown in full lines in Figs. 2 and 4, one of a plurality of balls 60 disposed in the pocket 53 may gravitate through the aperture 55 into the pocket 57. Then when the slide is moved to the position wherein it is shown in dotted lines in Fig. 2, the ball will gravitate from the pocket 57 through the aperture 58 onto the track 52. A member 61 is preferably provided for guiding the balls 60 through the aperture 55.

Associated with the substantially straight track 52 is a hammer member 63 which may

be constructed of wood or any other suitable material. The hammer member 63 is secured to the free end of a lever 64 which is pivotally secured by a screw 65 to the plate 20. Springs 66 normally hold the lever 64 in the position wherein it is shown in Fig. 7. The lever 64 is provided with an extension 67 which projects through a slot 68 formed in the side wall 12. When one of the balls 60 is fed onto the track 52 by way of the aperture 58, the lever 64 may be manually displaced against the action of the springs 66 and then released to cause the hammer member 63 to propel the ball around the arcuate track 51. If the ball 60 is propelled with sufficient force, it will roll along the entire length of the arcuate track 51 and fall into the pocket 53. If the ball 60 is not propelled with sufficient force to cause it to roll along the entire length of the arcuate track 51, it will fall from some point along the upper portion of the track 51. Disposed within the arcuate track 51 and formed upon the front side of the plate 20 are a plurality of spaced pockets 70, 71, 72 and 73. When the ball 60 falls from the upper portion of the track 51 it may be caught by any one of the pockets 70, 71, 72 and 73, or it may fall between these pockets into the pocket 53. The lower ends of the pockets 70, 71, 72 and 73 are normally closed by pins 75 projecting from a bar 76, which is slidably journaled in back of the plate 20, the pins 75 projecting through slots 77 formed in the plate 20. A spring 79 yieldingly holds the bar 76 in a position wherein the pins 75 close the lower ends of the pockets 70, 71, 72 and 73. One end of the bar 76 projects through the side wall 13 so that it may be manually displaced against the action of the spring 79 to bring the pins 75 out of the positions wherein they close the lower ends of the pockets. Obviously, when a ball 60 falls into one of the pockets 70, 71, 72 and 73, it is retained therein until the bar 76 is displaced against the action of the spring 79.

The above described apparatus may be employed to play a game which resembles the ordinary baseball game. Thus, various values may be assigned to each of the pockets 70, 71, 72 and 73. For instance, if a ball 60 falls into the pocket 70, 71, 72 or 73, the player may be said to have made a first-base hit, a second-base hit, a third-base hit, or a homerun, respectively. If the ball 60 passes between the pockets 70, 71, 72 and 73, or falls through the arcuate track 51 into the track 53, the player may be said to have made a "strike". It will be readily understood that two or more players can play a game consisting of nine or any other number of innings. When the ball 60 falls into one of the pockets 70, 71, 72 and 73, it is retained therein until its position has been noted and the bar 76 has been actuated

to bring the pins 75 out of the positions wherein they close the lower ends of the pockets.

The operation of the above described apparatus is substantially as follows: A coin or token is inserted in the slot 36 and falls into the shallow groove 38. The lever 45 is then brought into the position wherein it is shown in dotted lines in Fig. 2 and one of the articles 26 passes from the pocket 33 through the aperture 42^b into the pocket 44. At the same time one of the balls 60 passes from the pocket 57 through the aperture 58 onto the track 52. The player then 15 angularly displaces the lever 64 against the action of the springs 66 any desired distance. The lever 64 is then released, whereupon the ball 60 is driven around the track 51 and either falls into one of the pockets 20 70, 71, 72 and 73 or falls between these pockets into the pocket 53. If the ball returns immediately to the pocket 53, a "strike" is called against the player. If the ball drops into any one of the pockets 25 70, 71, 72 and 73, the player is credited with either a first-base hit, a second-base hit, a third-base hit, or a homerun. The ball 60 is then returned to the pocket 53 by displacing the bar 76 in the manner above described. The slide 31 is retracted to its normal position by the springs 31^a. When the slide 31 has returned to its normal position, another article 26 falls into the pocket 33 and another ball 60 falls into the pocket 57. The next player may then operate the mechanism.

In the preferred embodiment of the invention I provide four balls 60 of different colors as indicated in Fig. 6. Each of the pockets 70, 71, 72 and 73 is colored to correspond to one of the balls 60 as indicated in Fig. 1. The players then attempt to drop each ball 60 in that pocket which corresponds to it in color. This requires considerable skill. Obviously, arbitrary values may be assigned to the several pockets 70, 71, 72 and 73 so that if a player drops a ball in the proper pocket he is credited with a certain score. If the player succeeds in dropping all of the balls in their proper pockets he will receive a score equal to the sum of the values assigned to the several pockets together with an added arbitrary value.

It is to be distinctly understood that apparatus comprising the above described game can be used apart from the dispensing mechanism as it does not form an essential part thereof. Thus the dog 41 may be omitted from the apparatus to permit the operation thereof without the insertion of a coin or token in the slots 36, and it is not necessary that articles be vended from the pocket 25.

Having thus described my invention, it is

obvious that various immaterial modifications may be made in the same without departing from the spirit of my invention; hence I do not wish to be understood as limiting myself to the exact form, construction, arrangement and combination of parts herein shown and described or uses mentioned.

The term "horizontal portions" as employed in my claims is intended to include a track having a portion which is inclined to the horizontal so that the ball will roll into a position where it may be struck by the hammer.

What I claim as new and desire to secure by Letters Patent is:

1. In a device of the kind described, an arcuate track disposed in a substantially vertical plane, means for propelling a ball along the track, a plurality of spaced pockets for catching the ball when it drops from the track, a pocket disposed below said plurality of pockets and adapted to catch the ball when it falls between said plurality of pockets, said lower pocket being adapted to hold a plurality of balls, and means for feeding the ball from said lower pocket to said propelling means.

2. In a device of the kind described, an arcuate track disposed in a substantially vertical plane, means for propelling a ball along the track, a plurality of spaced pockets for catching the ball when it drops from the track, a pocket disposed below said plurality of pockets and adapted to catch the ball when it falls between said plurality of pockets, said lower pocket being adapted to hold a plurality of balls, and means including a slide for feeding the ball from said lower pocket to said propelling means.

3. In a device of the kind described, an arcuate track disposed in a substantially vertical plane, spring-actuated means for propelling a ball along the track, a plurality of spaced pockets for catching the ball when it drops from the track, a pocket disposed below said plurality of pockets for catching the ball when it passes between said plurality of pockets, said lower pocket being adapted to hold a plurality of balls, means for retaining the ball in said plurality of pockets, means for causing the last-mentioned means to release said ball, and means for feeding the ball from said lower pocket to said propelling means.

4. In a device of the kind described, a track disposed in a substantially vertical plane, a plurality of differently colored balls, means for propelling the balls along the track, a plurality of spaced differently colored pockets for catching the balls when they drop from the track, the pockets being colored to correspond to the balls, a pocket disposed below said plurality of pockets and adapted to catch the balls when they fall

between said plurality of pockets, and means for feeding the balls one by one from said lower pocket to said propelling means.

5. In a device of the kind described, a track disposed in a substantially vertical plane, a plurality of differently colored balls, means for propelling the balls along the track, a plurality of spaced differently colored pockets for catching the balls when they drop from the track, the pockets being colored to correspond to the balls, a pocket disposed below said plurality of pockets and adapted to catch the balls when they fall between said plurality of pockets, and means including a slide for feeding the balls one by one from said lower pocket to said propelling means.

6. In a device of the kind described, an arcuate track disposed in a substantially vertical plane, a plurality of differently colored balls, spring-actuated means for propelling the balls along the track, a plurality of spaced differently colored pockets for catching the balls when they drop from the track, the pockets being colored to correspond to the balls, a pocket disposed below said plurality of pockets and adapted to catch the balls when they fall between said plurality of pockets, and means for feeding the balls one by one from said lower pocket to said propelling means.

7. In a device of the kind described, a track disposed in a substantially vertical plane, a plurality of differently colored balls, means for propelling the balls along the track, a plurality of differently colored spaced pockets for catching the balls when they drop from the track, a pocket disposed beneath said plurality of pockets and adapted to catch the balls when they fall between said plurality of pockets, said lower pocket being adapted to hold a plurality of balls, and means for feeding the balls one by one from said lower pocket to said propelling means.

8. In a device of the kind described, an arcuate track disposed in a substantially vertical plane and commencing with a substantially horizontal track portion, means

for propelling a ball along said track, said means being disposed in proximity to the horizontal portion of the track, a plurality of spaced means engageable by the ball when it falls from the track, a pocket disposed below said plurality of means and positioned above the said horizontal track portion, said pocket arranged to receive the ball each time it falls between or to one side of said plurality of means, and means for feeding the ball from the pocket to the horizontal track where it is engageable by said propelling means.

9. In a device of the kind described, an arcuate track disposed in a substantially vertical plane, means for propelling a ball along said track, said means being associated with the track at the lower extremity thereof, a plurality of spaced means engageable by the ball when it falls from the track, a pocket of inclined formation disposed between said plurality of means and above the lower extremity of the track and arranged to receive the ball each time it falls between or to one side of said plurality of means, and means for permitting the ball to be fed from said inclined pocket outwardly to the lower extremity of the track for engagement with said propelling means.

10. In a device of the kind described, an arcuate track disposed in a substantially vertical plane and commencing with a substantially horizontal track portion, propelling means operatively associated with the said track extremity for propelling the ball over the horizontal track portion and thence the arcuate track portion, a plurality of spaced means engageable by the ball when it drops from the arcuate track portion, means for maintaining the ball isolated from the propelling means when the said ball falls from the arcuate track, and a mechanically actuated device for releasing said means and permitting the ball to gravitate to the extremity of said horizontal track for engagement with said propelling means.

In testimony whereof, I have hereunto signed my name.

OTTO J. DOERRE.
